(57) **CLAIM**

The ornamental design for a display screen with graphical user interface, as shown and described.

DESCRIPTION

FIG. 1 is a front view of a display screen with graphical user interface showing our new design;

FIG. 2 is another front view thereof, being identical to the view of FIG. 1 except for the indicia indicating the area for enlargement shown in FIG. 3; and,

FIG. 3 is an enlarged view of the region identified by the indicia in FIG. 2.

The broken line showing of the remainder of the user interface and display screen is for environmental purposes only and forms no part of the claimed design.
